CLAIM

The ornamental design for a bullet shaped letter opener, as shown and described.

DESCRIPTION

FIG. 1 is a perspective view of a bullet shaped letter opener shown in a casing.

FIG. 2 is a perspective view of the bullet shaped letter opener of FIG. 1 shown removed from the casing with the letter opener portion shown in phantom for completeness of illustration.

FIG. 3 is a side view of the bullet shaped letter opener of FIG. 1 shown in the casing.

FIG. 4 is a side view of the bullet shaped letter opener shown removed from the casing with the letter opener portion shown in broken lines.

FIG. 5 is a top view of the bullet shaped letter opener of FIG. 3.

FIG. 6 is a right side view of the bullet shaped letter opener shown removed from the casing with the letter opener portion shown in broken lines; and,

FIG. 7 is a bottom view of the bullet shaped letter opener of FIG. 3.

The broken lines shown in the drawings form no part of the claimed design.
